UNITED STATES PATENT OFFICE.

WALTER J. BAUROTH, OF COLUMBUS, OHIO, ASSIGNEE TO THE JEFFREY MANUFACTURING COMPANY, OF COLUMBUS, OHIO, A CORPORATION OF OHIO.

ELECTRIC MOTOR.

1,125,039.

Specification of Letters Patent.

Patented Jan. 19, 1915.

Application filed December 7, 1907. Serial No. 405,593.

To all whom it may concern:

Be it known that I, WALTER J. BAUROTH, a citizen of the United States, residing at Columbus, in the county of Franklin and 5 State of Ohio, have invented certain new and useful Improvements in Electric Motors, of which the following is a specification, reference being had therein to the accompanying drawing.

10 This invention relates to an electric motor and the improvements have to do more especially with the armature shaft, the bearings, and the casing structure.

15 The nature and objects of the invention will appear from the following description in connection with the accompanying drawings.

20 In the drawings, Figure 1 is a side elevation of a motor embodying my improvements, mounted upon the driving axle of a locomotive or car, the rear drive wheel being removed; Fig. 2 is a horizontal sectional view taken on the line 2--2 of Fig. 1; Fig. 3 is a fragmentary vertical section 25 through the commutator end of the armature shaft and shaft support; and Fig. 4 is a fragmentary section through the pinion end of the armature shaft in the plane of separation of the field frame.

30 Referring in detail to the construction illustrated, 1 designates, as an entirety, the motor which has a field frame of the box type divided along diagonal lines into an upper part 2 and a lower part 3.

35 4 and 5 are bolts which pass through lugs formed integral with the field frame parts to clamp the latter securely together. Each part of the frame is provided with two pole pieces, as indicated, and which need not be 40 described in detail, as they constitute no part of my invention. The upper part 2, of the field frame, is provided with a suspension nose 6, while the lower part 3 is pivotally mounted upon the locomotive or car axle 7, being provided with suitable bearings 8, so that the axle 8 turns freely with respect to the motor frame.

45 Instead of providing the armature with a rotatable shaft mounted in stationary 50 bearings, I provide the armature, indicated as an entirety by 9, with a central sleeve 10, which rotates upon a stationary shaft 11 rigidly mounted in the field frame. A commutator 12 is mounted upon one end of the 55 sleeve 10 and to the opposite end of the

sleeve a pinion 13 is rigidly secured, said pinion having a tubular extension which fits snugly within the enlarged bore at the end of the sleeve and is locked in position by the bolt 14. Bearing sleeves 15 are 60 forced one into the commutator end of the sleeve and the other into the bore of the pinion 13. Within these bearings the stationary shaft 11 is received. Collars 16 and 17 are rigidly secured to the pinion and commutator ends, respectively, of the shaft 11 by pins 16^a—17^a. These collars are clamped between the upper and lower sections 2 and 3 of the field frame, being held against rotation by the outer ends of the pins 16^a—17^a 70 which project into slots or grooves in the frame casting, as is clearly indicated.

The collar 16, instead of being mounted in the end wall proper of the field frame as is the collar 17, is clamped between the 75 upper and lower parts 18^a, 18^b of the cylindrical extension 18 which projects from the adjacent end wall of the frame and constitutes a housing for the pinion.

80 The pinion 13 meshes with the spur gear 19, which is fast on the axle 7. A gear casing consisting of upper and lower parts 20—21, is provided to inclose the spur gear 19, this casing being radially open on the motor side to fit a corresponding opening 85 in the cylindrical extension 18 of the field frame. It will be seen that the cylindrical extension 18, together with the casing 20—21, constitute a housing which completely incloses the pinion and gear. The two 90 parts of the gear casing are secured together by bolt 22 and the whole is supported upon the motor frame by bolts 23 and 24.

95 The shaft 11 is preferably made hollow, as shown, to receive lubricant, which may be led to the bearing surfaces through the radially drilled holes 25. The lubricant is preferably fed to the hollow shaft through a tube 26, which carries at its outer end an oil cup 27. The tube 26 is preferably inserted through a hole in the collar 17 and threaded at its inner end into the shaft 11, as is clearly shown. 11^a are screw plugs to close the ends of the shaft 11.

100 It will be seen that oil or grease escaping from the bearing at the pinion end of the shaft will fall into the gear casing and help to lubricate the gearing. To prevent the lubricant escaping from the other bearing from coming in contact with the commu- 105 110

tator, the collar 17 is provided on its inner face with an inwardly projecting flange 17^b which forms a groove into which the oil escaping from the bearing is thrown, and 5 from which it escapes through the drain passage or nozzle 17^c, which projects through a slot in the end wall of the field frame.

It will be seen that by removing the 10 upper part 2 of the field frame, the armature is freed and may be lifted together with the shaft 11 and its supporting collars 16 and 17 from the lower part 3 of the field frame. It will also be seen that with the 15 construction which I provide although the bearings are far apart and are practically unrestricted as to length, the longitudinal over all dimension of the motor is reduced to a minimum.

What I claim is:

- 20 1. In an electric motor, the combination of the field frame, an armature shaft having its ends rigidly supported by the end walls of said frame, the armature sleeve surrounding said shaft, the hollow pinion positioned beyond the end of the armature 25 sleeve and rigidly connected with said sleeve at the said end, and bearing sleeves interposed one between and directly engaging the said shaft and hollow pinion, the other 30 interposed between and directly engaging said shaft and the armature sleeve, substantially as set forth.
2. In an electric motor, the combination of the field frame having an outward extension on one of its end walls, the armature 35 shaft having its ends rigidly mounted one in said outward extension, the other in the opposite end wall of the field frame, the armature sleeve surrounding said shaft, the hollow 40 pinion rigid with said sleeve at one end thereof, and bearing sleeves interposed one between said shaft and hollow pinion, the other between said shaft and the armature 45 sleeve, substantially as set forth.
3. In an electric motor, the combination of the field frame composed of two parts separable along diametral lines, the armature shaft, collars rigidly secured to the

ends of said shaft and clamped between the parts of said frame, and the armature sleeve 50 rotatably mounted on said shaft, substantially as set forth.

4. In an electric motor, the combination of the field frame formed with an axial, outward extension on one of its end walls and composed of two parts separable along diametral lines through said extension, the armature shaft, the collars rigidly secured to the ends of said shaft and clamped one 55 between the parts of said extension, the other between the two sections of the opposite end wall of the frame, the armature sleeve rotatably mounted on said shaft, and the pinion rigid with said sleeve and disposed within said extension, substantially as 60 set forth.

5. In an electric motor, the combination of the field frame having an end wall formed with an axial, outward extending pinion housing with a lateral opening to receive a 70 gear, said frame being composed of two parts separable along diametrical lines through said housing, the armature shaft having its ends clamped one between the parts of the pinion housing, the other between the two sections of the opposite end 75 wall of the frame, the armature sleeve rotatably mounted on the shaft, a pinion rigidly secured to said sleeve at one end thereof and disposed within the said housing, and a 80 separate gear casing having a lateral opening fitted to the lateral opening of the pinion housing.

6. In an electric motor, the combination of the field frame composed of two parts 85 separable along diametral lines, the stationary armature shaft clamped in position by the parts of said frame, and the armature sleeve rotatably mounted on said shaft, substantially as set forth.

In testimony whereof I affix my signature, in presence of two witnesses.

WALTER J. BAUROTH.
